Primary Examiner — Joseph Kukella*Assistant Examiner* — Darryl J Dardenne(74) *Attorney, Agent, or Firm* — McAndrews, Held & Malloy, Ltd.(57) **CLAIM**

The ornamental design for a collection tray for a drink maker, as shown and described.

DESCRIPTION

FIG. 1 is a top front perspective view of a collection tray for a drink maker showing our new design;

FIG. 2 is a bottom perspective view thereof; and,

FIG. 3 is a front elevation view thereof.

The dashed broken lines in the figures illustrate portions of the collection tray for a drink maker that form no part of the claimed design. Views of the collection tray for a drink maker that are not shown in the figures form no part of the claimed design.
